UNITED STATES PATENT OFFICE.

FRED LUX, OF WATERBURY, CONNECTICUT, ASSIGNOR OF ONE-HALF TO PAUL LUX,
OF WATERBURY, CONNECTICUT.

MOTOR.

1,198,735.

Specification of Letters Patent. Patented Sept. 19, 1916.

Application filed December 29, 1913. Serial No. 809,285.

To all whom it may concern:

Be it known that I, FRED LUX, a citizen of the United States, residing at Waterbury, in the county of New Haven and State of Connecticut, have invented a new and useful Improvement in Motors; and I do hereby declare the following, when taken in connection with the accompanying drawings and the characters of reference marked thereon, to be a full, clear, and exact description of the same, and which said drawings constitute part of this application, and represent, in—

Figure 1 a front view of a motor constructed in accordance with my invention in its position of rest. Fig. 2 an end view. Fig. 3 a rear view. Fig. 4 a top or plan view. Fig. 5 a rear view with the weight in its raised position and the rack at the limit of its upward movement preparatory to moving downward, this figure showing the armature down ready to be raised by its spring. Fig. 6 a detached view of the driving gear and the stop ratchet in connection therewith, showing the position assumed after the weight has started in its downward movement. Fig. 7 a similar view of the gear with the ratchet removed. Fig. 8 a perspective view of the stop ratchet, detached.

This invention relates to an improvement in motors, and particularly to motors in which the power is derived from a weight which weight is in turn operated by intermittently applying electromagnetic power.

The object of this invention is to provide a motor adapted for operating mechanical display devices for show windows either by direct application or through a pendulum; and the invention consists in the construction hereinafter described and particularly recited in the claims.

In carrying out my invention, I employ a suitable frame herein shown as consisting of a front plate 2 and a rear plate 3 connected by posts 4. Mounted between the plates is a main shaft 5 on which is loosely mounted a pinion 7 and fixed to the pinion is a fly wheel 6. The pinion 7 meshes with a rack 8 loosely mounted on a shaft 9, and formed with an upwardly projecting arm 10 to which a weight 11 is secured. This rack is also provided with a rearwardly extending stud 12 insulated from the rack and adapted to be engaged by an arm 13 secured to a collet 35 which is rigidly mount-

ed on the shaft 9, said collet also carrying an armature arm 14 connected with an armature 15 directly over the poles of electromagnets 16 one terminal of the coils being connected with a binding post 17 forming part of the rearwardly projecting stud 12; and the other terminal connected with a binding post 18 which is insulated from the frame. The frame itself is provided with a binding post 19. On the shaft 9 is a coil spring 20 the tendency of which is to lift the armature. Fixed to the shaft 5 is a ratchet wheel 21 adapted to be engaged by a pawl 22 pivotally connected with the fly wheel 6 and forced into engagement with the ratchet wheel by a spring 23. Loose upon the shaft 5 is a large gear wheel 24 provided near its hub with a segmental slot 25 to receive a pin 26 projecting inward from a ratchet wheel 27 which is rigid upon the shaft 5 and adapted to be engaged by a pawl 28 mounted on an arbor 29 and pressed by a spring 36 to engage with the ratchet wheel 27 to prevent reverse movement. Fixed to the large gear wheel 24 is a spring 30 which engages with the forward face of the pin 26 for the purpose as will hereinafter appear. The gear wheel 24 meshes with a pinion 31 fixed to a shaft 32 which carries a driving disk 33 through which power may be transmitted directly to the device to be operated or adapted to operate the pendulum.

If desired, a driving disk 34 may be fixed directly to the driving shaft 5 as shown in Fig. 4; and it is apparent that if desired the driving disk 33 may be omitted, and power derived from the disk 34. The advantage of this will be to derive greater power.

Starting from the position shown in Fig. 1, electrical current is applied through the binding posts 18 and 19 to energize the magnet 16, the circuit being closed through the engagement of the arm 13 with the stud 12 which will draw the armature 15 downward, and this downward movement of the armature suddenly raises the arm 13, so as to rapidly rotate the fly wheel 6. The fly wheel having had momentum imparted to it, will continue to rotate after the armature strikes the rack, and this continued movement of the fly wheel will go on to raise the weight until the power imparted to the fly wheel is exhausted, at which time

the weight will be raised to the position shown in Fig. 5. This continued upward movement of the arm 8 carries the stud 12 out of engagement with the arm 13 and 5 thus breaks the circuit, allowing the armature to assume its normal position, under the action of the spring 20. In the upward movement of the weight the rack rotates the pinion 7 and the fly wheel 6 connected 10 with it during which movement the pawl 22 carried by the fly wheel rides freely over the ratchet 21, but engages the ratchet the moment the weight starts on its downward movement. As the weight begins to 15 descend the pawl 22 engaging with the ratchet 21 turns that ratchet and thus the shaft 5 which in turn moves the ratchet 27, which by the engagement of the pin 26 with the slot 25 will, after the pin has moved 20 through the length of the slot 25, move the gear wheel 24 and hence turn the disk 33. This movement of the pin 26 has placed tension on the spring 30 so that after the ratchet 27 has imparted movement 25 to the gear 24 it will allow that gear to have additional movement corresponding to the length of the slot 25 while the weight is again being thrown up by the electromagnets owing to the fact that the stud 12 30 again comes into contact with the arm 13 to close the circuit. The slight movement imparted by the spring 30 is sufficient to keep the disk 33 moving while the weight is rising. It will thus be seen that the operation 35 of the disk is practically continuous as it is moved forward on each downward movement of the weight, and is provided with sufficient movement by the spring 30 beyond that directly imparted to it by the weight 40 to insure its continuous rotation during the time occupied by the weight in rising.

I claim:—

1. In a motor, the combination with a driving shaft, of a fly wheel loosely mounted 45 thereon, a weighted rack adapted to turn said fly wheel, connections between the fly wheel and the driving shaft, and electrical means for intermittently imparting movements to the fly wheel to raise the said 50 weighted rack.

2. In a motor, the combination with a driving shaft, of a pinion loosely mounted thereon, a fly wheel connected with the said pinion, a rack meshing with said pinion, 55 a weight connected with the said rack, connections between the fly wheel and driving shaft, and electrical means for intermittently imparting movement to the fly wheel to raise the said weight.

60 3. In a motor, the combination with a driving shaft, of a pinion loosely mounted thereon, a fly wheel connected with said pinion, a pivotal rack meshing with said

pinion, a weight attached to said rack, a stud connected with said rack and insulated therefrom, a pivotal arm with which said stud may engage, an armature adapted to raise said arm whereby the weight and rack are lifted, a magnet adapted to depress said armature, said weight adapted to be thrown upward beyond the movement of said rack whereby electrical contact between the arm and the stud is intermittently broken. 65

4. In a motor, the combination with a frame, of a shaft mounted therein, a pinion 75 loosely mounted on said shaft, a fly wheel connected with said pinion, a pivotal rack meshing with said pinion, a weight connected with said rack, an electromagnet, an armature adapted to lift said rack, a ratchet 80 connected with said shaft, a pawl on said fly wheel adapted to turn said ratchet, a gear wheel fixed to said shaft, and connections between the ratchet and gear wheel whereby the gear is revolved by the falling 85 of said weight.

5. A motor comprising a main shaft, a pinion loosely mounted thereon, a fly wheel connected with said pinion, a pivotal rack meshing with said pinion, a weight connected with said rack, an electromagnet including an armature, an arm raised by said armature and adapted to lift said weight, a ratchet wheel on said shaft, a pawl carried by said fly wheel and adapted to turn 95 said ratchet, a gear wheel loosely mounted on said shaft and formed with a segmental slot, a stop ratchet provided with a pin entering the slot in the gear, a disk, and connections between the disk and gear whereby 100 by the falling of the weight said disk will be turned.

6. A motor comprising a main shaft, a pinion loosely mounted thereon, a fly wheel connected with said pinion, a pivotal rack 105 meshing with said pinion, a weight connected with said rack, an electromagnet including an armature, an arm raised by said armature and adapted to lift said weight, a ratchet wheel on said shaft, a pawl carried by said fly wheel and adapted to turn said ratchet, a gear wheel loosely mounted on said shaft and formed with a segmental slot, a stop ratchet provided with a pin entering the slot in the gear, a spring 110 connected with the gear and bearing on said pin, a disk, and connections between the disk and gear whereby by the falling of the weight said disk will be turned.

In testimony whereof, I have signed this 115 specification in the presence of two subscribing witnesses.

FRED LUX.
